UNITED STATES PATENT OFFICE.

SIMON W. WARDWELL, OF PROVIDENCE, RHODE ISLAND, ASSIGNOR TO WARDWELL BRAIDING MACHINE COMPANY, OF PORTLAND, MAINE, A CORPORATION OF MAINE.

BRAIDING-MACHINE.

1,197,692.

Specification of Letters Patent. Patented Sept. 12, 1916.

Application filed December 12, 1913. Serial No. 806,278.

To all whom it may concern:

Be it known that I, SIMON W. WARDWELL, a citizen of the United States, residing at Providence, in the county of Providence and State of Rhode Island, have invented certain new and useful Improvements in Braiding-Machines, of which the following is a specification.

My invention consists of improvements in 10 braiding machines and relates particularly to that class of machines in which the yarn- or thread-supplies are arranged in series and revolved in opposite directions about a common axis. In this type of machine the 15 braiding process is carried out by deflecting the strands or yarns from one set of supplies to cause them to follow a sinuous course in and out around the supplies of the other set.

The object of my improvement is to simplify 20 the structure and arrangement of the mechanism for controlling and regulating the deflection of the yarns in sinuating their course around the axis of the machine.

In carrying out my improvement I have 25 decreased the number of parts of the operating-mechanism and reduced their weight, thus being enabled to minimize the effects of momentum and inertia on the moving elements and to therefore provide for a 30 higher rate of operation and increased production of the whole machine. In addition, my improved construction provides for greater accessibility of the operating-mechanism for oiling and adjusting the parts; 35 and also for easier and more simple methods of construction which make for economy in the cost of manufacture.

The invention is fully set forth in the following specification, illustrated by the accompanying drawings, in which like reference 40 characters designate like parts.

In the drawings:—Figure 1 is a front view of my improved braiding machine, shown part sectional in a vertical plane extending 45 through its main axis; Fig. 2 is a developed plan view of a section of the machine, showing several of the supply-carriers for the upper set of yarn-supplies and illustrating the arrangement of the driving 50 means therefor and the relation of the yarn-controlling devices thereto; Fig. 3 is an enlarged, underneath, plan view of one of the supply-carriers, looking in the direction indicated by the arrow z , Fig. 1, and showing 55 the relation thereto of one of the yarn-

controllers which operates to deflect the sinuating yarn to one side or the other of the carrier; Fig. 4 is an enlarged, side view of the yarn-controller; Fig. 5 is an enlarged, plan view of the controller-bracket; Fig. 6 shows a modification in the arrangement of the cam-mechanism for operating the yarn-controllers.

The present machine is similar in general respects to that described in my United States Patent No. 1,032,870 dated July 16, 1912. As illustrated particularly in Fig. 1 of the present drawings it comprises a main frame or standard A and two oppositely rotating heads or turrets B and C. The outer 70 turret B has a bearing or a series of balls b mounted in a race a on the main frame A, and the inner turret C is supported on the balls c which are held in a race b' on the turret B. The outer turret B carries a bevel-gear ring B' which, as here shown, is secured thereto by the pins b^2 ; while the inner turret C has a downwardly-extending portion C' to which is attached a bevel-gear ring C^2 held in place by the pins c' , or 80 through any other suitable means. The driving-shaft D for the machine is mounted in an overhanging bearing d secured to the main frame A, and carries at its outer end the driving-pulley D' or other suitable 85 means for rotating the shaft. Mounted on the inner end of the shaft D and secured thereto by suitable means, such, for instance, as the pin d' , is a bevel-pinion E adapted to mesh with the bevel-gears B' and C^2 on the 90 turrets B and C. The pulley D' is connected with the shaft D through suitable clutch-devices, not here shown or described, and when power is applied thereto to turn the shaft the gear E serves to rotate the turrets 95 B and C in opposite directions as previously explained.

Mounted on the outer turret B and projecting radially therefrom is a series of brackets F, F, etc., which support the lower tier of yarn-cops, spools or other supplies Y, Y. Suitable tension-devices f , f , etc., on the brackets F act to control the delivery of the yarns y from the cops Y, but these are not here shown in detail as they form no part of the present invention. The yarn-supplies X, X, etc., of the upper tier are arranged above the cops Y, Y with their axes extending at right-angles to those of the lower cops, so that they incline toward 110 the lower cops, y .

the main axis of the machine. The yarn-cops X are mounted on movable supply-carriers G, G, etc., which are constructed with lenticularly-shaped deck-portions g , see Figs. 5 2 and 3, and depending, arcuate runners g' . At the forward or leading ends of the carriers G the runners g' are pointed and project beyond the decks g in sharp, prow-like extensions g^2 . Referring again to Fig. 1, 10 the runners g' are preferably wedge-shaped in cross-section and are fitted to slide in a correspondingly-shaped groove or race h formed in the annular track H. The track H is formed as a part of the outer rim of 15 the turret B and is split up into segments h', h' , see Fig. 2, leaving openings above the supply-brackets F in which the yarns y from the lower supplies are allowed to play back and forth to adapt them to pass inwardly or outwardly around the carriers G. 20 Any suitable number of yarn-supplies may be employed on the machine and usually the number of cops Y in the lower tier will equal the number of supplies X in the upper tier. As here shown the machine is adapted 25 for eight supplies in each tier. The number of track-sections h' also corresponds to the number of supplies in each tier and when the carriers G for the upper supplies are in 30 the position illustrated in Fig. 2 the openings in the track H will register with the spaces between the ends of the carriers.

The carriers G are caused to revolve about the axis of the machine in the direction opposite to that taken by the lower yarn-supplies Y, and slide in the track H, passing from one section to another across the openings therebetween. The carriers G are impelled to travel on the track H by means of 35 drivers J, J, etc., mounted on the turret C. Referring particularly to Fig. 2, two drivers J are provided for each carrier, each being disposed in a conico-radial guideway c^3 in the conical rim c^4 of the turret C, see Fig. 1. 40 The guideways c^3 consist of slots formed in the upstanding portion of the rim c^4 and where the rim overhangs the rim b^3 of the turret B the slots are cut clear through the former. Set into the rim b^3 of the turret B 45 is a conical cam-plate K formed with the cam groove k , see also Fig. 2. On the under side of each driver J is a stud or roll j fitted to the cam-groove k and adapted to ride therein. The outer ends of the drivers J 50 are adapted to engage with slots or openings g^3 formed in the upstanding lugs g^4 on the carrier-decks g . As the turret B and the attached cam-plate K rotate in the opposite direction to that of the turret C, in which latter the drivers are mounted, the cam-groove k will act on the rolls j to alternately project the drivers J into and withdraw them from engagement with the carriers G. The arrangement of the drivers J with respect

is at all times engaged by one of its drivers and the drivers of each pair are withdrawn from and returned into engagement with the carrier one after another. This provides that the yarns y from the lower supplies, as 70 they sinuate through the upper supplies, will be allowed to pass by on the inside of the carriers, that is, between the carriers and their driving-turret C, without obstruction from the drivers. The drivers J are held 75 in place in their guideways in the turret C by the overlapping, conical rim l of a central member L, which takes the form of a cover or bonnet mounted to rotate on an inner, tubular standard M which surmounts 80 the main frame A. The yarns x from the upper supply-cops X pass through suitable tension-devices, not here shown, and draw up across the top of a beater-device N which projects upwardly from the center of the 85 bonnet L. The yarns y from the lower supply-cops Y also converge at this point and merge with the yarns y to form the braid W which is fed from the machine by suitable take-up devices not here shown and de- 90 scribed.

In the machine of my patent previously referred to the means for shifting the yarns from the lower supplies to deflect them in and out around the upper supplies consists 95 of switches, so-called, arranged to alternately open and close the passageways between the carriers and their driving-head or turret. In this previous arrangement the switches are operated from a cam or cams inclosed 100 within the main framework of the machine. In my present improvement I dispense with the switches and direct the sinuating yarns through the means of controlling-members O arranged around the rim of the turret B 105 and operated from a cam also positioned on the outside of the machine. The controllers O for the sinuating yarns or threads y consist of a novel form of crotch-like members having divergent arms or branches across 110 which the lower yarns draw as they lead up past the upper supply-carriers G. Normally, the yarns y rest in the central crotch or depression o^4 of the controllers O and are influenced by the movement of the latter to 115 be deflected slightly one way or the other to pass them by the supply-carriers G. The yarns y are free, however, to slide outward on the branches o^2, o^3 of the crotch when they pass into engagement with the curved 120 edges of the carriers G, the latter having a plow-like action to force the yarns aside. The arrangement and method of operation of this part of the machine will now be described in detail.

The controllers O are preferably constructed of relatively stiff wire, as shown more particularly in Figs. 3 and 4, or they might be made from sheet-metal if desired. During the rotation of the main crotch

portion O' and an offset slide-bar or rod O^2 , the latter having its lower end formed up with a flat bottom or foot-piece o . The foot-piece o serves as a shoe adapted to slide on the face p of the operating cam P , as more particularly explained hereinafter. If desired, the end of the slide-bar O^2 could be provided with a bearing for a roller arranged to roll on the cam P , but as the movement required of the controller is relatively slight and since its positioning need not be defined with extreme accuracy, such provision against wear is not important. The controllers O are preferably arranged to slide in bearings carried on the brackets F which carry the lower yarn-supplies Y , it being understood that there is a controller provided for each yarn y , all arranged on the outside of the turret B in appropriate relation to the tension-devices f . As here shown the controllers O are mounted in bearings formed on auxiliary brackets R , the latter being secured to the main brackets F by means of the screws f' which attach said brackets F to the turret B , see Fig. 4. The brackets R are here illustrated as formed up from sheet-metal, but they might be constructed as castings, made integral with the brackets F . Each bracket R is formed with a main plate-portion r having a hole r' through which the screw f' passes, see Figs. 3, 4 and 5. Bent at right-angles to the plate r is an arm r^2 formed with two opposite, hook-like guiding-lugs r^3, r^4 . Beneath the lug r^4 is a third guiding-lug r^5 bent around in the opposite direction, and at the bottom of the extension r^6 of the plate r is a U-shaped guide-bearing r^7 . The slide-bar O^2 of the controller O is adapted to slide in the guiding-lugs or bearings r^3, r^5 and r^6 and is held from turning therein by the lug r^3 which engages the elbow-portion o' of the offset crotch-portion O' , see Fig. 4. The controller O might be operated by gravity to maintain its foot-piece or shoe o bearing against the face of the cam P , but I prefer to employ a relatively light spring S for this purpose. As here shown, the spring S is secured at its lower end to a lug r^8 on the bracket extension r^6 and its upper end is hooked around the offset elbow-portion o' of the controller O . The main crotch-portion O' of the controller O is illustrated more particularly in Fig. 3, and comprises the two curved arms o^2, o^3 which diverge from the central V-shaped depression or guideway o^4 , with the outer arm o^3 terminating in the hook o^5 . The hook o^5 acts to prevent the yarn y from accidentally sliding off from the end of the branch o^3 , and the curved form of the two arms o^2, o^3 is designed to assist the yarn in sliding down into the depression o^4 . Formed up from an extension of the arm r^2 of the bracket R is a looped finger r^9 which serves as a guard to prevent the

yarn y from catching in the projecting portions of the bracket and also assists in threading it into the crotch of the controller O .

Referring now to Fig. 1, the cam P which operates the yarn-controllers O is here shown as being constructed as a part of a ring-member T which is mounted on the main frame A of the machine. The member T serves as a brake-ring and is formed with a tapered face t adapted to frictionally engage a correspondingly-shaped face b^4 on the turret B to check the rotation of the latter and cause a prompt stopping of the machine. This engagement is effected through a slight rotary movement of the brake-ring which acts to bring into engagement suitable wedge-devices for forcing the ring up against the turret. These devices are fully set forth in my United States Patent No. 1,008,504, granted Nov. 14, 1911, and need not here be described in detail as they form no part of the present invention. Suffice it to explain that the brake-ring T has only a very limited movement, either around the machine or in an upward direction, and that normally, during the operation of the braiding-mechanism, it remains stationary on the frame A , being held in position by suitable detent-means. For this reason, and since it has a convenient location, I make use of the brake-ring T as a support for the circular cam P , as before described. I have also preferred to show the cam P as made integral with the ring T , but it might be constructed as a separate part attached thereto. It is also obvious that the cam P could be attached to or made a part of the main frame A , its essential characteristic being that during the operation of the machine it remains stationary with respect to the rotating turret B which carries the yarn-controllers O . In Fig. 2, I have shown a development of one form of the cam-face p of the cam P and its relation to the controllers O . As here illustrated, the face p of the cam is formed with a series of four rises p', p' and an equal number of alternately arranged depressions p^2, p^2 . The controllers O are shown in alternate engagement with the high and low points of the cam and this arrangement is adapted for producing "plain" braid, so-called. With this style of cam the controllers are shifted to cause each lower yarn y to pass first to the outside of two of the upper yarn-carriers G ; then on the inside of the next two carriers; next on the outside of the following two carriers and so on around the machine as more particularly pointed out hereinafter. Other forms of cams can be substituted to vary the timing of the operation of the controllers and in this way any particular pattern can be produced in the fabric, such, for instance, as "basket" braid, so-called, in which the

yarns interweave over and under each other singly. Still other and more complicated patterns can be arrived at by providing more than one cam for operating the controllers. That is to say, any suitable number of cams could be provided, with the controllers arranged with different groups or series engaging different cams. For instance, two cams could be attached to the ring T with the controllers arranged in alternate engagement therewith, or with alternate pairs of the controllers engaging each cam. In Fig. 6 I have illustrated such a construction of the ring T and by offsetting the lower ends of the controllers O different ones can be made to engage the different cams P and P'. If desired, four cams of different forms could be provided and with such simple changes a great variety of patterns can be produced in the braid.

The operation of the complete machine is as follows: The yarns x from the upper supply-cop X are led through tension-devices, not here shown, and thence to the gathering 25 or braiding-point above the center of the machine. The yarns y from the lower supply-cops Y are threaded through the tension-devices f, thence across the crotch-portions O' of the controllers O and up to the 30 braiding-point where they merge with the yarns x. When power is applied to the drive-shaft D the turret B is turned in the direction indicated by the arrow 2, Fig. 2, and the turret C is rotated in the opposite 35 direction as indicated by the arrow 3. The turret C is connected by the drivers J to slide the carriers G on the track H, with the carriers traveling in the direction indicated by the arrow 3, while the track is rotating in the opposite direction, as indicated 40 by the arrow 2. The turret B carries, besides the track H, the supply-cops Y and the yarn-controllers O so that these latter pass the carriers G during their revolution in the 45 opposite direction thereto. The tension applied to the yarns y as they draw up from the cops Y tends to normally maintain each yarn in the crotch or guideway o' of its controller. As the controllers ride over the undulating face of the cam P, which latter is stationary on the main frame of the machine, a slight oscillation, or rising and falling motion, will be transmitted to them to deflect the yarns y to one side or the other 50 of the sharp prowgs g' of the carriers G. The yarns y are thus engaged by the prowgs g' with a sort of selective action which serves to put them to one side or the other until they come into contact with the curved edge 55 of the carrier-deck. The edge of the deck then acts to plow the yarns aside to pass them by the yarn-cops X carried by the carriers. During this action the yarns y will slide outwardly and inwardly across the 60 arms o², o³ of the controllers O, but after 65

passing each carrier each yarn y will slide back again into the guiding-crotch o' so as to assume its proper position to be directed by the controller against one side or the other of the next carrier. This oscillating motion of the controllers which acts to shift the yarns y with respect to the carriers G can be regulated according to the pattern desired in the fabric through the employment of different forms of cams as previously described. 70 75

Referring to Fig. 2, the cam P here shown in developed contour will actuate the controllers with respect to the carriers in the following manner: Starting with the controller O at the extreme left-hand, this is shown with its foot-piece or shoe o on the low point p² of the cam-face p. Consequently the controller will be in its lowermost position and it is to be noted that the 80 guideway or crotch o' is so related to the prow g' of the carrier G that the yarn y will pass to the inside of the latter as the two move toward each other. That is to say, the yarn y will come into contact with the pointed prow g' on its inner side as the controller moves in the direction indicated by the arrow 2, and the carrier moves in the direction indicated by the arrow 3. Now, during this opposite movement of the controller and carrier the yarn y will be pushed to the inside by the prow g', and coming into contact with the curved edge of the carrier-deck g it will be still further deflected toward the axis of the machine so as to pass 85 90 95 it by on the inside of the supply-cop X. As the yarn y passes through the opening or channel between the carrier G and its driving-turret C the drivers J are alternately withdrawn from engagement with the carrier to prevent obstruction to its movement, this action taking place through the operation of the cam K as previously described. In this way the yarn y is caused to pass by the supply-cop X so that it will weave in 100 105 110 under the yarn x at this point in the formation of the braid W. The cam P here illustrated has four high points and four low points, and there are eight carriers G, and eight controllers for the lower yarns y. 115 Hence, since the cam P remains stationary while both the carriers G and yarn-controllers O are rotating in opposite directions at equal rates of speed, any one controller will pass from the low point to the high point of 120 the cam only after it has passed by the leading points or prowgs of two carriers. Considering the first left-hand controller, for example, this will remain depressed or in its lowermost position until it reaches the 125 position of the next controller to the right as illustrated in Fig. 2, and during this time the carrier next adjacent the controller to the right will have passed it, and the succeeding or following carrier will also have met the 130

controller and passed it to such an extent that the yarn will be deflected to its inner edge. Stated briefly, with the arrangement here shown, each controller deflects its yarn *y* to the inside of two carriers before being shifted to throw the yarn onto the outside of a carrier. In the same way, the second controller from the left, as shown in Fig. 2, will deflect its yarn on to the outer edges of two passing carriers before being shifted to pass the yarn to the inside, and this sequence of operations takes place all around the machine. It is also called to attention that, with this arrangement of the yarn controllers in alternate engagement with the high and low points of the cam, while any one of the lower yarns *w* is passing over two of the upper yarns *x* the next following yarn *y* will pass under the first one of this pair and over the other one. In other words, each following yarn *y* splits the pair of yarns *x* which the previous yarn *y* has passed over and the same thing occurs in passing the yarns *y* under the yarns *x*, so that the crossing of the yarns is progressive and the pattern resulting is what is usually termed "plain" braid. It will also be observed that it is a very simple matter to alter the form of the cam *P* to produce a single over and under motion of the yarns for producing "basket" braid, or to employ several cams for making more complicated patterns.

The essential feature of novelty of my invention consists in the means for controlling the sinuating yarns without engaging them rigidly or positively. That is to say, the yarns *y* are not threaded through guide-eyes or hooks operated by articulated, swinging arms to move them through relatively long, arcuate paths or with an extended up and down movement. It is particularly called to attention that the movement of the yarn-controllers is very slight, merely a small fraction of an inch, and the main deflection of the yarns is effected through the plow-like action of the carriers as they pass through the shed of the yarns. In other words, my improved form of yarn-controller simply acts to shift the yarn a very slight distance so that it engages with one side or the other of the prow of the carrier and further deflection is caused by the engagement of the yarn with the edge of the carrier. The novel crotch-like form of the yarn-controller here shown provides that the yarn will always return to its normal position in the crotch or guideway so as to assume its proper relation to the leading ends of the carriers which it meets in its path around the machine. At the same time the yarn is not restricted by the controller from passing freely in or out around the carrier. That is to say, it can be slid readily on the branches of the crotch so as to provide for

an unhindered passage over or under the several supply-ops of the upper tier. It is my belief that this novel form of shiftable crotch-member for controlling the yarns which are to be deflected to one side or the other of the passing carrier, while allowing them to slide in and out on the controller without hindrance, is entirely new in the art. The principal advantages resulting from this improvement are as follows: The yarns are not subjected to undue tension or strain in directing their course through the machine; neither are they chafed or abraded from being passed through guide-eyes or from being bent at sharp angles. Reference to Fig. 1 will illustrate this point as it will be seen that the yarns *y* are deflected but very slightly from a straight course between their supplies and the braiding-point. Another point to be noted is that the movement required of the controllers for the yarns is very slight and furthermore the cam for operating the controllers is of relatively great diameter so that no abrupt rises on its engaging face are required. These features make for greater durability of the mechanism and also provide for a higher speed of operation and increased production of the whole machine. In addition, the operating parts being arranged on the outside of the machine are more accessible for oiling and adjustment, and the whole mechanism is much more simple and easier to manufacture.

Various modifications besides those herein specified might be made in the form and structure of my new device without departing from the spirit or scope of the invention.

Therefore, without limiting myself to the exact construction shown and described, what I claim is:—

1. In a braiding machine, the combination with a plurality of yarn-supplies arranged in sets revolving in opposite directions, of yarn-controllers having guideways in which the yarns are normally maintained under the tension thereon, said guideways formed with branches across which the yarns are free to play, and means to actuate the controllers to shift the yarns to cause them to be deflected in and out around the supplies of the other set.

2. In a braiding machine, the combination with a plurality of yarn-controllers provided with crotch-like guideways for the yarn to draw across and branches extending laterally therefrom to adapt the yarn to play therealong after it has been deflected out of the guideways, and means to shift the position of the yarn-controllers radially with respect to the axis of the machine during the operation thereof.

3. In a braiding machine, the combination with two sets of yarn-supplies, of means to

- rotate one set of supplies with respect to the other set, yarn-controllers having diverging yarn-guiding branches along which the yarns from one set of supplies are adapted to play and notches intermediate the guiding-branches in which the yarns are normally maintained by the tension of their draft, and means to actuate the yarn-controllers to direct the yarns radially inward or outward 10 during the rotation of their supplies past the supplies of the other set.
4. In a braiding machine, the combination with a plurality of yarn-supplies arranged in sets revolving in opposite directions, 15 of yarn-controllers having guiding-faces against which the yarns from one set of supplies are held under tension, said yarn-controllers arranged to guide the yarns in a mean orbital path around the machine while 20 allowing them to be deflected therefrom to play radially across their guiding-faces, and means to operate the controllers to shift the yarns to cause them to be deflected in and out around the supplies of the other set.
5. In a braiding machine, the combination with a plurality of carriers revolving about the axis of the machine, of a series of yarn-supplies carried by said carriers, a second series of yarn-supplies revolving in the opposite direction, means to guide the yarns from the second series of supplies in a definite orbital path with respect to the carriers of the first series, said means adapted to permit said yarns to play freely inward 35 or outward in a radial direction without restriction except from the contact of the yarns therewith to allow the carriers to deflect the yarns from their mean path, and means to shift the yarn-guiding means radially with respect to the axis of the machine 40 during their revolution therearound.
6. In a braiding machine, the combination with a plurality of yarn-supplies arranged in sets with the supplies of one set revolving past those of the opposite set, of shiftable 45 yarn-controllers for the yarns of one set of supplies, said yarn-controllers having substantially radial guiding-faces across which the yarns draw and depressions in said guiding-faces for maintaining the yarns in a mean orbital path as the supplies are revolved about the axis of the machine, while also allowing the yarns to be deflected radially out of the depressions to play along 50 the guiding-faces to pass the yarns in and out around the supplies of the other set, and means to shift the yarn-controllers intermittently during the operation of the machine.
7. In a braiding machine, the combination 55 with two sets of yarn-supplies, of means for revolving the supplies of one set with respect to the supplies of the other set, yarn-controllers having guiding-crotches through which the yarns from one set of supplies draw and lateral branches extending from 60 each side of the crotches in a direction substantially radial to the axis of the machine, and means to actuate the yarn-controllers to direct the yarns to one side or the other of the supplies which they pass whereby the 70 yarns are deflected thereby out of the guiding-crotches along the branches of the controllers and then drawn back into the crotches after they have passed the supplies.
8. In a braiding machine, the combination 75 with a plurality of yarn-supplies arranged in sets with the supplies of one set revolving past those of the other set, of carriers for carrying one set of supplies, yarn-controllers having guideways across which the 80 yarns from the other set draw to maintain them in a normal path of revolution while allowing them to be deflected radially therefrom, said controllers formed with portions diverging laterally from their guideways to 85 lead the yarns back to normal position therein after they have been deflected therefrom, and means to operate the controllers to shift the yarns to cause them to be deflected by the carriers to pass them in and 90 out around the supplies carried thereby.
9. In a braiding machine, the combination 95 with a plurality of yarn-supplies arranged in sets revolving in opposite directions about a common axis, of means to periodically shift the position of the yarns leading from one set of supplies to cause them to be deflected in and out around the supplies of the other set, said means comprising oscillating controllers having crotch-portions acting to normally maintain the 100 yarns in a predetermined relation to the axis of the machine, but adapted to allow the yarns to play radially in and out with respect to the crotches whereby said yarns 105 are adapted to pass around the oppositely-moving yarn-supplies without having their free movement restricted by the controllers.
10. In a braiding machine, the combination 110 with a plurality of yarn-supplies arranged in sets revolving in opposite directions, with the yarns from one set leading past the supplies of the other set, of controllers traveling with one set of supplies and passing the supplies of the other set, 115 said controllers having crotch-portions adapted to normally maintain their related yarns in a predetermined relation to the passing supplies but to allow the yarns to play across the branches of their crotches 120 as they pass around said supplies, and means to shift the controllers to regulate the order of passing of the yarns in and out around the supplies.
11. In a braiding machine, the combination 125 with a plurality of yarn-supplies arranged in sets revolving in opposite directions about the axis of the machine, of yarn-controllers having crotch-like guideways across which the yarns from one set of sup-
- 65 70 75 80 85 90 95 100 105 110 115 120 125 130

plies draw, devices for maintaining tension on the said yarns to normally retain them in the crotches of the controllers, and means to operate the controllers to shift the yarns to a relatively slight extent only to cause them to be deflected to one side or the other of the supplies of the other set during which movement of deflection the yarns are forced out of the crotches of the controllers while passing around the said supplies.

12. In a braiding machine, the combination with a plurality of yarn-supplies arranged in sets revolving in opposite directions about the axis of the machine, of a series of crotch-like yarn-controllers across which the yarns from the supplies of one set lead, said yarn-controllers formed with divergent branches extending laterally from their crotches across which the yarns are adapted to play, and cams engaging said controllers in series to operate the latter to shift the yarns to a relatively slight extent only whereby they will be caused to be deflected by the action of the supplies of the other set to follow a sinuous course to effect the braiding operation.

13. In a braiding machine, the combination with two sets of yarn-supplies, of a rotating member for carrying one set of supplies, a second member, rotating in the opposite direction, means to revolve the other set of supplies by and with the second member, yarn-controllers mounted on the first member and formed with crotches for guiding the yarns from the supplies carried by said member, said controllers also having branches extending laterally from their crotches across which the yarns are free to play, and a cam to operate said controllers to shift the yarns to a relatively slight extent only to cause them to be deflected by the action of the supplies revolving in the opposite direction to sinuate one set of yarns through the other set.

14. In a braiding machine, the combination with two rotating turrets, of two sets of yarn-supplies revolved in opposite directions by said turrets, carriers for one set of supplies, yarn-controllers carried by one turret and formed with crotches across which the yarns from the supplies on said turret draw, said controllers also having branches diverging from their crotches across which the yarns are free to play, and a stationary cam for oscillating said controllers to shift the yarns to a relatively slight extent only to cause them to be deflected from the crotches in opposite directions by the action of the carriers of the other set of supplies.

15. In a braiding machine, the combination with two sets of yarn-supplies, of revolving carriers to carry one set of supplies, means to revolve the other set of supplies past said carriers in the opposite direction, yarn-controllers revolving with the second

set of supplies, said controllers having crotches across which the yarns from said second set of supplies draw, and branches diverging from the crotches along which the yarns are free to play, and means to operate the controllers to direct the yarns to one side or the other of the ends of the carriers whereby the latter act to deflect the yarns out from the crotches to pass them around the supplies carried by the carriers. 70

16. In a braiding machine, the combination with two sets of yarn-supplies, of carriers revolving about the axis of the machine and carrying one set of supplies, means to revolve the other set of supplies in the opposite direction, yarn-controllers revolving with the second set of yarn-supplies, said controllers formed with guiding-crotches through which the yarns normally draw, and branches diverging from their crotches along which the yarns are free to play, and means to actuate the controllers to shift the yarns to either side of the leading ends of the carriers whereby the latter act to deflect the yarns out from the guiding-crotches to pass them around the supplies carried by the carriers. 85

17. In a braiding machine, the combination with two sets of yarn-supplies, of plow-like carriers revolving about the axis of the machine and carrying one set of supplies, means to revolve the other set of supplies in the opposite direction, yarn-controllers revolving with the second set of supplies, said yarn-controllers having crotches 100 through which the yarns normally draw and branches diverging therefrom along which the yarns are free to play, and means to operate the controllers to cause them to shift the yarns to one side or the other of the carriers whereby the carriers coöperate therewith to lift the yarns out of the crotches and to deflect them around the supplies carried by the carriers. 95

18. In a braiding machine, the combination with two sets of yarn-supplies, of a plurality of lenticularly-shaped carriers for carrying one set of supplies, means to revolve the carriers about the axis of the machine, means for revolving the other set of 110 yarn-supplies in the opposite direction, yarn-controllers revolved with the second set of supplies, said yarn-controllers formed with guiding-crotches adapted to regulate the normal positions of the yarns and 120 branches extending from the crotches along which the yarns are free to play, and means to shift the yarn-controllers to determine the point of engagement of the yarns with the leading ends of the carriers whereby the 125 latter pass either to one side or the other of each yarn.

19. In a braiding machine, the combination with two sets of yarn-supplies, of carriers for one set of supplies formed with 130

lenticularly-shaped sides and pointed ends, means to revolve the carriers and their supplies about the axis of the machine, means to revolve the other set of supplies in the opposite direction, yarn-controllers revolving with the second set of supplies, said controllers formed with crotch-like guideways in which the yarns from the adjacent supplies normally lie and branches across which the yarns are adapted to play, and means to operate the controllers during their movement around the machine to cause them to direct the yarns to one side or the other of the pointed ends of the carriers whereby the sides of the carriers act to disengage the yarns from the crotches and to slide them on the branches of the controllers in passing them around the supplies carried by the carriers.

20. In a braiding machine, the combination of two turrets rotating in opposite directions, an annular track on one of the turrets, carriers adapted to slide on the track and to carry a set of yarn-supplies, driving means on the second turret to slide the carriers around the track, means for carrying another set of supplies on the first turret, yarn-controllers carried on the first turret and arranged adjacent the yarns from the supplies, said yarn-controllers having crotches through which the yarns draw and lateral branches along which the yarns are free to play, and a cam to shift the controllers to determine the positions of the yarns in relation to the carriers to cause them to be deflected by the action of the carriers to pass them to one side or the other of the supplies carried thereby.

21. In a braiding machine, the combination with two sets of yarn-supplies, of carriers for revolving one set of supplies, said carriers formed with lenticularly-shaped sides and sharp-pointed prow-like projections on their leading ends, means to revolve the other set of supplies in the opposite direction from the carriers, yarn-controllers

carried by said means, said yarn-controllers formed with crotches through which the yarns draw and lateral branches along which the yarns are free to play, and means to oscillate the controllers during their movement past the carriers to shift the yarns drawing through the crotches to direct them to one side or the other of the prow of the carriers whereby the sides of the latter engage the yarns to deflect them out from the crotches of the controllers and pass them by the supplies carried by the carriers.

22. In a braiding machine, the combination with carriers for revolving one set of yarn-supplies about the axis of the machine, of sliding yarn-controllers revolved past said carriers with the other set of supplies, said controllers formed with crotches through which the yarns draw and branches extending laterally therefrom along which the yarns are free to play, a cam engaging the ends of the controllers to reciprocate the latter, and resilient means for maintaining the controllers in engagement with the cam.

23. In a braiding machine, the combination with a plurality of yarn-supplies arranged in sets revolving in opposite directions, of carriers for carrying one set of supplies, yarn-controllers having crotches engaging the yarns from the other set of supplies while allowing them to move free of the crotches and laterally therefrom without restricting the movement of said yarns in certain directions, and means to actuate the controllers to shift the yarns engaging therewith to cause the latter to coact with the supply-carriers to be deflected thereby to one side or the other of the supplies carried by said carriers.

In testimony whereof I affix my signature in presence of two witnesses.

SIMON W. WARDWELL.
